UNITED STATES PATENT OFFICE.

LYMAN G. LEASE, OF HOWLAND, OHIO.

CONCRETE BLOCK AND WALL.

1,013,407.

Specification of Letters Patent.

Patented Jan. 2, 1912.

Application filed October 11, 1909. Serial No. 522,067.

To all whom it may concern:

Be it known that I, LYMAN G. LEASE, citizen of the United States, residing at Howland, in the county of Trumbull and State 5 of Ohio, have invented certain new and useful Improvements in Concrete Blocks and Walls, of which the following is a specification.

This invention has for its object an improved construction of wall and building blocks or tiles therefor, the said blocks being formed on one or more faces with a groove or depression designed to produce 10 ventilating openings through the walls. And the invention consists in certain constructions, arrangements and combinations 15 of the parts that I shall hereinafter fully describe and claim.

For a full understanding of the invention, reference is to be had to the following description and accompanying drawings in 20 which:

Figure 1 is a sectional perspective view of a portion of a wall constructed with my improved building blocks, illustrating an arrangement whereby longitudinally and substantially continuous air passages are formed in the wall. Fig. 2 is a perspective view of one form of block employed; Fig. 30 3 is a similar view of a modified form of block; and, Fig. 4 is an end view of one arrangement of the blocks hereinafter specifically referred to.

Corresponding and like parts are referred 35 to in the following description and indicated in all the views of the accompanying drawings by the same reference characters.

Referring to the drawing, the numeral 1 designates one form or embodiment of my 40 improved building block or tile, which may be made of any desired substance such as concrete, or vitrified materials as desired. The blocks 1 are formed in one wall with an inwardly curved longitudinally extending portion, as indicated at 2, producing on 45 the exterior of the block a longitudinally extending groove or depression 3, which is preferably a little deeper than the wall or side of the block, as shown. By producing 50 this groove, as shown in the drawing, it will be noted that the wall of the block or tile is not weakened, but is substantially of uni-

form thickness. It is to be understood that these grooves may be formed in one or more of the walls of the block or tile, and may be 55 formed either along the median line of the wall of the block or at either side of such line. The grooves 3 are preferably semi-circular in cross section. Obviously the blocks may be arranged in the building wall 60 with the grooves of the two adjoining blocks meeting so as to produce a cylindrical ventilating opening as illustrated in Fig. 4. Or, the grooved wall of one block may be arranged contiguous to the straight or plane 65 walls of the two adjacent blocks, so as to provide air passages as indicated by the direction of the arrows in Fig. 1.

From the foregoing description in connection with the accompanying drawings, it 70 is obvious that a wall built of blocks constructed in accordance with my invention may be provided with ventilating openings extending longitudinally and continuously in any desired course by laying the blocks 75 end to end, and that any one or more of the courses may be provided with transversely extending ventilating openings by placing any one or more of the blocks transversely of the wall, that is, with its groove 80 extending from front to rear.

Obviously my invention is not limited to a hollow block or tile, nor to a hollow block or tile as illustrated in Fig. 1. For instance, as illustrated in Fig. 3, a modified form of 85 block designated 1^a, may be used. This block may be provided with a web 4 and with the grooves 3^a in opposite walls at opposite sides of the web.

Having thus described the invention, what 90 is claimed as new is:

A wall constructed of a plurality of courses of hollow blocks, the blocks being open from end to end and those of each course being laid end to end whereby to afford an 95 uninterrupted air passage extending the entire length of each course, each of the blocks being formed in one wall with a depression extending the entire length thereof, that portion of the wall of each block opposite 100 the depression being plane, the blocks of each course being arranged alternately with the depressed wall of each block presented in the same direction as the plane wall of

the adjacent blocks of the same course, the depression of each block registering throughout a portion of its length with the depression of a related block of an adjacent course whereby to establish communication at intervals between the air passages of the adjacent courses.

In testimony whereof I affix my signature in presence of two witnesses.

LYMAN G. LEASE. [L. s.]
